UNITED STATES PATENT OFFICE.

CASSIMIR BOHACHIK, OF CHICAGO, ILLINOIS.

BULLET-FIRING ALARM-LOCK.

1,296,747.

Specification of Letters Patent. Patented Mar. 11, 1919.

Application filed August 27, 1917. Serial No. 188,373.

To all whom it may concern:

Be it known that I, CASSIMIR BOHACHIK, a subject of the Emperor of Austria, residing at Chicago, in the county of Cook and 5 State of Illinois, have invented certain new and useful Improvements in Bullet-Firing Alarm-Locks, of which the following is a specification.

The present invention relates to locks, and 10 more particularly to those of the type adapted to prevent unauthorized tampering and opening of the locks.

The primary object of the invention is the 15 provision of a door lock adapted for shooting a person attempting to release the securing mechanism of the lock without previously actuating a safety mechanism arranged therewith, while an audible alarm is adapted to be automatically sounded at 20 a distant point upon releasing the mechanism.

A further object of the invention is the 25 provision of a door lock adapted for shooting a person unfamiliar with the lock mechanism who attempts to pick the lock or in any manner to release the same in an unauthorized manner, the structure being such that a person familiar therewith may readily manipulate the lock without being injured.

A still further object of the invention is 30 to provide a ready means in connection with a door lock for shooting any unauthorized persons attempting to manipulate the lock mechanism, while an authorized person may readily operate the lock without actuating the firing mechanism arranged therewith while a distantly positioned alarm will be sounded whenever the bolt of the lock is released.

In the drawings forming a part of this 35 application and in which like designating characters refer to corresponding parts throughout the several views,

40 Figure 1 is an elevational view of a portion of a door and its casing illustrating the present device installed thereon.

Fig. 2 is a vertical sectional view thereof.

45 Fig. 3 is a horizontal sectional view of the same, with the mechanism locked.

Fig. 4 is a view similar to Fig. 3 with the mechanism released.

50 Fig. 5 is a view of the mechanism casing with the front plate removed and bolt pro- jected.

Fig. 6 is a view of the mechanism casing with the top plate removed.

Fig. 7 is a sectional view taken upon line VII—VII of Fig. 6.

Fig. 8 is a sectional view taken upon line VIII—VIII of Fig. 6.

Fig. 9 is a sectional view taken upon line IX—IX of Fig. 6.

Fig. 10 is an enlarged detail view partially in section of a portion of the firing 65 mechanism of the lock and the door upon which the same is mounted, showing the safety mechanism released.

Fig. 11 is a view of a portion thereof 70 showing the safety mechanism in its operative arrangement.

Fig. 12 is a vertical sectional view taken upon line XIII—XII of Fig. 10, and

Fig. 13 is a perspective view of a key employed with the device.

Referring more in detail to the drawings 75 it will be understood that the device is adapted for employment with either inside or outside doors and the said lock is herein illustrated in connection with a door 10 80 having a casing 11, the exterior of the door structure being illustrated in Fig. 1 of the drawings and showing the appearance of the present structure as seen by a person approaching the outside of the door, the es- 85 cutcheon plate 12 shooting barrel 13 and the safety release rod 14, alone being visible and being hereinafter fully described.

The mechanism casing 15 for the lock structure is secured to the inner side of the 90 door 10 having a removable front plate 16 adjacent the door and also having a removable top plate 17. A U-shaped lock bolt 18 is slidably arranged within the end compartment 19 of the casing 15 adjacent the 95 cover plate 16, one arm 20 of the said bolt having internal teeth 21 forming a rack adapted to be engaged by the prism shaped ward 22 of an operating key 23 when the key is inserted through the key hole slot 24 100 of the plate 12 and also through the front plate 16 of the casing 15 and with the free end 25 of the key seated within a perforation 26 in the partition 27 arranged within said case. A keeper 28 is carried by the 105 door casing 11 having an entrance opening 29 adapted for the longitudinal movement of the bolt 18 therethrough when longitudinally actuated by the said key 23.

The lower arm 30 of the bolt 18 is pro- 110

vided with teeth 31 upon its outer edge also in the form of a rack, and arranged in mesh with a pinion 32 journaled upon the partition 27, a rocking finger 33 being also journaled upon the partition 27 having an ar-
5 cuate toothed portion 34 in mesh with the pinion 32. Circuit wires 35 leading to an alarm bell, not shown, and positioned at any desirable distant point either within the
10 building where the lock is installed or in a police station, are provided with any suitable form of circuit closer 36 being arranged with the circuit normally open and adapted for closing by pressing the push button 37.
15 The button 37 is arranged within the path of movement of the finger 33 and it will be evident that whenever the bolt 18 is re-
tracted, the pinion 32 will swing the finger 33 against the button 37 thereby closing the
20 circuit closer 36 for the wires 35 and ring-
ing the bell. The releasing of the lock mechanism is thereby denoted at any distant point whenever the door 10 is unlocked by withdrawing the bolt 18 from the keeper
25 opening 29.

A shaft 38 is journaled through the partition 27 and the opposite end 39 of the casing 15 and is arranged with a pinion 40 thereon in the compartment 19 in constant
30 mesh with the teeth 31 of the bolt 18. A driven shaft 41 is journaled within the casing 15 adjacent the shaft 38 while a pinion 42 upon the shaft 38 is in constant mesh with a pinion 43 upon the driven shaft 41
35 and whereby any movement of the bolt 18 will result in revolving the driven shaft 41. The gear 44 is arranged upon a shaft 45 in mesh with an idler pinion 46 upon a similarly positioned shaft 47 and which pinion
40 46 is in constant mesh with a pinion 48 ar-
ranged upon a shaft 49 which has one of its ends journaled in the casing end 39 and its other journaled through a block 50 ar-
ranged within the casing. A beveled gear
45 51 is carried by the shaft 49 in mesh with a gear 52 carried by a shaft 53 positioned at right angles to the shaft 49 and arranged parallel with the partition 27. An operating cam 54 is mounted upon the shaft 53
50 adapted for engaging the heel 55 of a ham-
mer 56 carried by a shaft 57 arranged parallel with the shaft 53.

A housing 58 for the firing mechanism is arranged inwardly of the partition 27 with
55 a firing barrel or tube 13 extending from the housing 58 and projecting forwardly of the front plate 16 and the door 10. A cartridge magazine 59 is journaled within the housing 58 upon a shaft 60 journaled in
60 the partition 27 and the casing end 39 for arranging the cartridges 61 carried by the magazine in operative alignment with the inner end of the barrel 13 and also in position to be exploded by the spring pressed
65 firing pin 62 arranged through the housing

58 within the path of movement of the ham-
mer 56. A gear 63 is arranged upon the shaft 60 of the magazine 59 for bringing successive ones of the cartridges 61 into fir-
ing position.

70

The means for releasing the safety mecha-
nism is in the form of a ball or handle 14 ar-
ranged upon the outer end of a rod 64 slid-
ably arranged through the door 10, plate 16
and partition 27 and arranged with a head 75
65 on its inner end having operative en-
gagement with a sleeve 66 for sliding the
said sleeve upon the driven shaft 41 upon
which the sleeve is splined as best illus-
trated in Fig. 11 of the drawings. A pin-
ion 67 is carried by the sleeve 66 adapted
for meshing with the gear 44 while a simi-
lar pinion 68 carried by the sleeve 66 is
adapted for meshing with the gear 63. A
stop 69 is arranged upon the casing end 39 85
adjacent the head 65 while a spring 70 in-
terposed between the head 65 and end 39
normally maintains the head 65 in engage-
ment with the inner end 71 of the stop 69
and at which times the pinions 67 and 69 are 90
in meshing relations with the gears 44 and
63 respectively.

From this detailed description of the in-
vention the complete operation thereof will
be apparent, the elements being illustrated 95
in their normal locking arrangement in such
figures as 1, 3, 6 and 9 and at which times
the bolt 18 is projected and the spring 70
maintains the safety mechanism 14 pro-
jected, while the finger 33 is spaced from the 100
push button 37. The positioning of the key
23 within the slot 24 engages the same with
the bolt teeth 21 so that the key may be
turned for retracting the bolt 18. As the
bolt 18 is retracted and released from its 105
keeper 28, the finger 33 is swung against the
push button 37 and retracts it for energiz-
ing an alarm as hereinbefore described. One
of the cartridges 61 will also be simulta-
neously fired through the barrel 13 at such 110
times for hitting the person who is tamper-
ing with the lock, such firing being effected
by means of the pinions 40, 42 and 43 which
are operated by the toothed lower arm 30 of
the bolt 18 and through the pinion 67. 115
Gears 44, 46 and 48 by means of the pinions
51 and 52 operate the cam 54 retracting the
hammer 56. A return spring 72 being ar-
ranged for the hammer 56 for violently con-
tacting the hammer 56 with the free end of 120
the firing pin 62 and exploding the adjac-
ently positioned cartridges 61. Any con-
venient shifting means for the cartridge
magazine 59 may be provided, such as the
aforementioned gear 63 carried by the shaft 125
60 and turned by the pinion 68 for bringing
one of the cartridges into firing position ad-
jacent the pin 62 at the instant the hammer
56 is released for firing the same. The hous-
ing 58 is cutaway upon its lower side which 130

permits the ready insertion of the cartridges 61 within the magazine 59 as illustrated in Fig. 12.

Any person who is familiar with the operation of the lock mechanism will push inwardly upon the safety mechanism 14 thereby disconnecting the pinions 67 and 69 before inserting the key 23 and under such circumstances it will be evident that the bolt 18 may be retracted without firing any of the cartridges 61, although the alarm will be sounded when the bolt is so retracted. The cartridges within the magazine 59 may be readily positioned at will with respect to the barrel 13 by manipulating the clutch head 65 as desired for moving the gear 63 and the magazine 59. A safety lock is arranged which is harmless when operated by a person familiar therewith but which is adapted for shooting an unauthorized person attempting to release the bolt 18 and being unfamiliar with the operation of the safety device 14.

What I claim as new is:—

1. A lock comprising a casing, a slidable bolt carried thereby, a cartridge magazine within the casing, a firing barrel arranged adjacent the magazine and extending forwardly of the casing, a firing pin for the magazine, an operating hammer for the pin, an actuating cam for the hammer, and operating connections between the cam and bolt, whereby the hammer is adapted for actuation upon the retracting of the bolt, controlling means for said operating connections and safety adjusting means for the controlling means operable at a point adjacent the free end of the barrel, automatic positioning means for the magazine associated with said operating means and an automatic alarm associated with the said bolt whereby the alarm is sounded when the bolt is retracted.

2. A lock comprising a casing, a sliding bolt arranged therein, a tubular barrel projecting from said casing, a housing within the casing and at the inner end of the barrel, a magazine in the housing adapted for holding cartridges and for alining the same with the barrel, a spring pressed firing pin carried by the housing, a swinging hammer for the pin, an operating cam for the hammer, a driven shaft, a slidable pinion splined on

said shaft, operative connections between the said pinion and cam, safety disengaging means for the said pinion, and operative connections between the said bolt and driven shaft.

3. A lock comprising a casing, a sliding bolt arranged therein, a tubular barrel projecting from said casing, a housing within the casing at the inner end of the barrel, a magazine adapted for holding cartridges and for alining the same with the barrel, a spring pressed firing pin carried by the housing, a swinging hammer for the pin, an operating cam for the hammer, a driven shaft, a slideable pinion splined on said shaft, operative connections between the said pinion and cam, safety disengaging means for the said pinion, the said bolt being U-shaped and having toothed upper and lower arms an operating key for the bolt adapted for reception through the forward side of the casing in operative connection with the upper arm of the bolt, and operative connections between the driven shaft and the lower arm of the bolt.

4. A lock comprising a casing, a sliding bolt arranged therein, a tubular barrel projecting from said casing, a housing within the casing at the inner end of the barrel, a magazine adapted for holding cartridges and for alining the same with the barrel, a spring pressed firing pin carried by the housing, a swinging hammer for the pin, an operating cam for the hammer, a driven shaft, a slideable pinion splined on said shaft, operative connections between the said pinion and cam, safety disengaging means for the said pinion, the said bolt being U-shaped and having toothed upper and lower arms an operating key for the bolt adapted for reception through the forward side of the casing in operative connection with the upper arm of said bolt, and operative connections between the driven shaft and the lower arm of the bolt, a shifting gear for said magazine, a pinion adapted for meshing with said gear arranged for simultaneous movement with the first named pinion, and an operating rod for said disengaging means terminating forwardly of the casing adjacent the free end of the barrel.

In testimony whereof I affix my signature.

CASSIMIR BOHACHIK.
